DECORATIVE WALL STRUCTURE

Application filed November 29, 1927. Serial No. 236,442.

The present invention relates, generally, to wall structures, and more particularly to decorative wall structure of sheet metal the exposed faces of which are provided with a vitreous enamel or other coating made to simulate marble, stone, or tiling. The invention also relates to structures and parts and combinations of parts for securing the decorative wall structure to a backing where-
10 by the securing or fastening arrangement is hidden from view, while the visual effect of mortar or cement joints is obtained.

An object of the invention is to provide a surface structure for walls for finishing and decorating purposes which is strong and which is simple and cheap to make and to apply.

Another object of the invention is to provide decorative wall paneling of coated sheet metal having preferably uncoated offset fastening or securing elements which can be covered and hidden from view by adjacent paneling and in some parts by the panels themselves.

25 Other objects and advantages of the invention, not at this time enumerated, will be apparent from the foregoing description of the arrangements and combinations of parts of a structure embodying the invention, from the drawings and from the appended claims; and the invention also consists in the statements, setting forth the structure and the arrangements and combinations of parts, made in the appended claims.

30 In the accompanying drawings, clearly illustrating the invention:

Figure 1 is a plan view in section of two walls joining at a corner and embodying the structure of the invention;

40 Figure 2 is a perspective view of a portion of a wall structure embodying the invention;

Figure 3 is a perspective view of a corner of a room in the walls of which is incorporated the structure of the invention;

45 Figure 4 is a plan view in section taken along the line 4—4 of Figure 3;

Figure 5 is a perspective similar to that of Figure 3, showing an alternate form of paneling;

Figure 6 is a vertical sectional view taken along the line 6—6 of Figure 1;

Figure 7 is a perspective view at a trans- 55 verse section of one of the forms of paneling structure of the invention; and

Figure 8 is a vertical section view of another form.

In each of the hereinabove described views of the drawings, similar reference characters are used to indicate corresponding parts. 60

Referring now to the drawings there is shown the metal panel 1 which is somewhat extensive in vertical length and in horizontal width, is made preferably, of a sheet 2 of iron, steel or other metal, and has formed, 65 unitarily therewith, attaching elements laterally disposed and comprising the perpendicular rearwardly directed flanges 3, 3 and the flanges 5, 5 offset from said flanges 3, 3. Over the outer surface of said sheet 2 70 is provided a layer 6 of enamel which has been vitrified thereon and which extends to a little distance over the rounded corners 8, 8 between the sheet 2 and the flanges 3, 3. In

Figures 1, 2 and 3 said panel 1 is shown as having an even surface to resemble large tiles or marble or stone slabs, and in Figure 5 panels 10, somewhat similar to panel 1, are shown as being grooved or scored in the manner of spaces between tiles so that the 75 enameled panel resembles a wall of tile. Said panels 1, 1 (or panels 10, 10) are secured to the walls 12, 12 by means of the screws 14, 14 or any other suitable fastening means 80 driven into said walls. The finish or appearance of said enamel 6 on said panels 1 can be plain white or colored, or the enamel can be colored or figured to simulate marble or stone, or to obtain other desired decorative 85 effects.

Because of the outward offset of said flanges 5, 5 from the panels 1 or 10 there will be a space between adjacent panels when fixed to a wall, and to fill said inter-panel spaces there is provided, as part of the invention, a longitudinal panel 16 having lateral flanges 17, 17 bent at an acute angle to the undersurface thereof to define a dovetail space 19, the distance between the panel 16 and the edge of a flange 17 preferably being 90 95 100

less than the distance between a panel 1 and its flange 5. Said panels 16 are fixed in place between corresponding panels 1, 1 (or 10, 10) by driving large headed nails 20, 20 into the walls 12, 12 with their heads left at a distance from said walls. The space between adjacent panels 1, 1 (or 10, 10) is then filled with a body 22 of cement or plaster or plaster of Paris and a panel 16 placed between said panels 1, 1 with its flanges 17, 17 pressed into said body of cement 22, said panel 16 being properly aligned with the adjacent panels 1, 1. Said body of cement 22 when set locks onto the heads of said nails 20, 20 and also onto said flanges 17, 17 thereby securely fastening said panels 16 in place. When the panels 16, 16 are put in place the cement 22 is smoothed off at the seam formed between adjacent edges of panels 1 (or 10) and 16 to provide the effect of a mortar joint 18 between the panels 1 and 16. Said panels 16 can be made quite narrow in which case a single row of nails 20, 20 is used for locking to the cement body 22, (see Figure 1), and the panels 16 can be quite wide in which case a row of the nails 20, 20 is provided adjacent to the position of each of the flanges 17, 17 thereof, (see Figures 1 and 4). The flanges 3, 3 serve to keep the body of cement 22 against lateral movement and therefore against any tendency to loosen. At corners between adjacent edges of panels 1, 1 (or 10, 10) there are provided narrow corner panels 25 which are similar to panels 16 except that they are curved to conform to the corner, and a row of the nails 20, 20 is provided in each of the adjacent walls to lock or retain a body of cement or plaster 28 in which the flanges 26, 26 of said corner panels 25 are imbedded. On both said panels 16 and 25 a coating or layer of vitrified enamel 29 is provided as on the panels 1 and 10. It is to be understood of course that the wall structure panels of the invention can be made without the coating of enamel in which case a decoration can be painted on either to simulate tiles or to make a plain coating or a fanciful design. The panels 1, 10, 16 or 25 can be extended to the ceiling of a room or they can terminate at an intermediate line in which case an overlapping moulding 21 can be used to cover the ends thereof, (see Figure 3), or a horizontal row or line of narrow panels 16 can be used to border the top of the assembled panels. Any or all of the panels can be made with fastening flanges at either their top or bottom edge or at both. The narrow panels 16 or 25 can be used to border the assembled panels at the bottom thereof also as shown in Figures 3 and 5.

In Figure 8 is illustrated a form of panel particularly adapted for base boards, and also for other purposes, which comprises a main panel portion 30, with offset securing flanges 31 and 32 at the top edge and, at the

bottom a concavely outwardly curved portion 33 and a convexly curved portion 34 bordered by an outer bottom edge 36 adapted to be embedded in a cement floor 38 adjacent a tile flooring 39, or otherwise fastened. Said panel 30 can have side fastening flanges similar to flanges 32, 31.

It is to be understood, of course, that the large panels 1 or 10 can be used without the narrow panels 16 or 25, or panels 16 without panels 1 or 10, and that other changes or modifications, not further indicated herein, can be made and that various changes and alterations in the arrangements and combinations of parts can be made without departing from the scope of the invention as set forth in the appended claims. Hence, I do not limit my invention as set forth in the statements in the claims to the particular structures or arrangements or combinations of parts as herein described and illustrated.

I claim:

1. A wall structure comprising a backing structure, a plurality of aligned sheet metal panels having offset securing elements fastened to said backing structure, said aligned panels having intermediate spaces, a cementitious material in said spaces, anchoring means in said backing structure embedded under said cementitious material, and an intermediate panel extending across the space between said adjacent panels and having lateral anchoring elements embedded in said cementitious material.
2. A wall structure comprising a backing structure, a plurality of aligned sheet metal panels having offset securing elements fastened to said backing structure, said aligned panels having intermediate spaces, a cementitious material in said spaces, anchoring means in said backing structure embedded under said cementitious material, an intermediate panel extending across the space between said adjacent panels and having lateral anchoring elements embedded in said cementitious material, said panels having a vitreous coating on their exposed faces, and said adjacent panels and intermediate panel being sized and spaced to disclose between their opposed edges the cementitious material underlying the latter panel to produce the effect of a mortar joint.
3. A wall structure comprising a backing structure, a plurality of aligned sheet metal panels having lateral rearwardly offset attaching flanges secured to said backing structure to mount said panels in spaced apart relation, anchoring means in said backing structure between adjacent panel edges, a cementitious material between adjacent panel edges embedding said anchoring means, and an intermediate panel extending between said adjacent panel edges and having lateral converging flanges embedded in said cementitious material.

4. A wall structure comprising a backing structure, a plurality of aligned sheet metal panels having lateral rearwardly offset attaching flanges secured to said backing structure to mount said panels in spaced apart relation, anchoring means in said backing structure between adjacent panel edges, a cementitious material between adjacent panel edges embedding said anchoring means, an intermediate panel extending between said adjacent panel edges and having lateral converging flanges embedded in said cementitious material, said panels having a vitreous coating on their exposed faces, and said adjacent panels and intermediate panel being sized and spaced to disclose between their opposed edges the cementitious material underlying the latter panel to produce the effect of a mortar joint.
- 5 10 15 20
- In testimony, that I claim the invention set forth above I have hereunto set my hand this 19 day of November, 1927.

CHARLES E. MAIER.
